UNITED STATES PATENT OFFICE.

WILLIAM H. GARDINER, OF NEW YORK, N. Y.

DESIGN FOR A BADGE, BUTTON, OR SIMILAR ARTICLE.

51,308.

Specification for Design.

Patented Feb. 26, 1918.

Application filed September 4, 1917. Serial No. 189,707. Term of patent 7 years.

To all whom it may concern:

Be it known that I, WILLIAM H. GARDINER, a citizen of the United States, residing at New York, in the county and State of New York, have invented a new, original, and ornamental Design for a Badge, Button, or Similar Article, of which the following is a specification, reference being had to the accompanying drawing, forming part thereof.

Figure 1 is a front elevation of a badge illustrating my new design;

Fig. 2 is a side view, and
Fig. 3 is a view of the back of the article.
I claim:

The ornamental design for a badge, button or similar article as shown.

WILLIAM H. GARDINER.

Witnesses:

ALBERT J. KAY,
JOHN C. DE LOCA.
